UNITED STATES PATENT OFFICE.

ELISABETH FRITSCHE, OF JERSEY CITY, NEW JERSEY.

DESIGN FOR A POST-CARD.

No. 38,566.

Specification for Design.

Patented May 14, 1907.

Application filed April 11, 1907. Serial No. 367,716. Term of patent 8½ years.

To all whom it may concern:

Be it known that I, ELISABETH FRITSCHE, a citizen of the United States, residing at Jersey City, Hudson county, State of New Jersey, have invented a new, original, and ornamental Design for a Post-Card, reference being had to the accompanying drawing, which represents a plan view of a post-card embodying the design.

I claim:

The ornamental design for a post card, as shown.

ELISABETH FRITSCHE.

Witnesses:

WILLIAM SCHULZ,
FRANK V. BRIESEN.
